US0D1006746S

(12) **United States Design Patent** (10) **Patent No.:** **US D1,006,746 S**
(45) **Date of Patent:** **** Dec. 5, 2023**

(54) **WIRELESS CHARGER FOR WATCH**

(71) Applicant: **GUANGDONG XIZHONGXI TECHNOLOGY CO., LTD.,**
Dongguan (CN)

(72) Inventor: **XiuHong Deng**, Shaoyang (CN)

(73) Assignee: **GUANGDONG XIZHONGXI TECHNOLOGY CO., LTD.,**
Dongguan (CN)

(**) Term: **15 Years**

(21) Appl. No.: **29/912,554**

(22) Filed: **Sep. 20, 2023**

(30) **Foreign Application Priority Data**

Jul. 27, 2023 (CN) 202330473179.2

(57) **CLAIM**

The ornamental design for a wireless charger for watch, as shown and described.

DESCRIPTION

FIG. 1 is a perspective view of a wireless charger for watch showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the wireless charger for watch that form no part of the claimed design.

1 Claim, 8 Drawing Sheets
